US0D1020699S

(12) **United States Design Patent** (10) Patent No.: **US D1,020,699 S**
(45) Date of Patent: ** *Apr. 2, 2024

(54) **REMOTE CONTROLLER**

(71) Applicant: **Mitsubishi Electric Corporation**,
Tokyo (JP)

(72) Inventors: **Satoshi Arai**, Tokyo (JP); **Hiroichiro Shimano**, Tokyo (JP); **Yuki Motomura**, Tokyo (JP); **Takanori Ikegaya**, Tokyo (JP)

(73) Assignee: **Mitsubishi Electric Corporation**,
Tokyo (JP)

(*) Notice: This patent is subject to a terminal disclaimer.

(**) Term: **15 Years**

(21) Appl. No.: **29/762,898**

(22) Filed: **Dec. 18, 2020**

(30) **Foreign Application Priority Data**

Jun. 18, 2020 (JP) ..... 2020-012105 D

(51) LOC (14) Cl. **14-03**

(52) U.S. Cl.

USPC **D14/218**

(58) **Field of Classification Search**

(57) **CLAIM**

The ornamental design for a remote controller, as shown and described.

DESCRIPTION

FIG. 1. is a perspective view of the front, right, and bottom sides of a remote controller showing our new design;

FIG. 2. is a front view thereof;

FIG. 3. is a rear view thereof;

FIG. 4. is a top plan view thereof;

FIG. 5. is a bottom plan view thereof;

FIG. 6. is a right side view thereof; and,

FIG. 7. is a left side view thereof.

The broken lines shown represent portions of the remote controller that form no part of the claimed design.

1 Claim, 7 Drawing Sheets
